Primary Examiner — Kevin K Rudzinski(74) Attorney, Agent, or Firm — Garvey, Smith & Nehrbass, Patent Attorneys, L.L.C.; Seth M. Nehrbass; Fabian M. Nehrbass(57) CLAIM

The ornamental design for a shirt, as shown and described.

DESCRIPTION

FIG. 1 is a front view of a shirt showing my new design; FIG. 2 is a rear view of the shirt; FIG. 3 is a front perspective view of the shirt; and, FIG. 4 is a side perspective view of the shirt.

The dashed lines in the figures showing a partial human figure illustrate the environment in which the article is used and do not form a part of the claimed design. The shading does not form a part of the claimed design.
